PIN-UP LAMP

Howard A. Julien, Wauwatosa, and Raymond
McCartan, Jr., Milwaukee, Wis.

Application December 18, 1948, Serial No. 150,233

Term of patent 14 years

(Cl. D48—4)

To all whom it may concern:

Be it known that we, Howard A. Julien and Raymond McCartan, Jr., both citizens of the United States of America and residents of Wauwatosa, in the county of Milwaukee and State of Wisconsin, and Milwaukee, in the county of Milwaukee and State of Wisconsin, respectively, have invented a new, original, and ornamental Design for a Pin-Up Lamp, of which the following is a specification, reference being had to the accompanying drawing, forming part thereof.

Fig. 1 is a bottom perspective view of a pin-up lamp showing our new design;

Fig. 2 is a side elevational view; and

Fig. 3 is a bottom plan view thereof.

We claim:

The ornamental design for a pin-up lamp, as shown.

HOWARD A. JULIEN.
